(57) **CLAIM**

The ornamental design for a dual-diameter, automotive hitch pin, as shown and described.

DESCRIPTION

FIG. 1 is a front side elevational view of a dual-diameter, automotive hitch pin showing my new design thereof, the rear-side elevational view being a mirror image thereof, FIG. 2 is a right side elevational view thereof, FIG. 3 is a left-side elevational view thereof, FIG. 4 is a top plan view thereof, FIG. 5 is a right-side elevational view of the dual-diameter, automotive hitch pin having a diameter expansion sleeve inserted into the pin, the rear side elevational view being a mirror image thereof,

FIG. 6 is a right side elevational view of FIG. 5 thereof, FIG. 7 is a left side elevational view of FIG. 5 thereof, FIG. 8 is a bottom plan view of FIG. 5 thereof; and, FIG. 9 is a top plan view of FIG. 5.

The hitch pin is shown separately from the sleeve in FIGS. 1-4 for ease of illustration.
